CLAIM

The ornamental design for a liquid container, as shown and described.

DESCRIPTION

FIG. 1 is a front perspective view of a liquid container; FIG. 2 is a front elevation view of the liquid container; FIG. 3 is a rear elevation view of the liquid container; FIG. 4 is a top elevation view of the liquid container; FIG. 5 is a bottom elevation view of the liquid container; FIG. 6 is a side elevation view of the liquid container; and, FIG. 7 is an opposite side view of the liquid container. The broken line portions of the disclosure are for the purpose of illustrating portions of the liquid container that form no part of the claimed design.
